UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

UNDERFRAME.

1,021,115.

Specification of Letters Patent. Patented Mar. 26, 1912.

Application filed August 1, 1911. Serial No. 641,821.

To all whom it may concern:

Be it known that I, VICTOR M. SUMMA, residing at 915 Olive street, St. Louis, Missouri, and being a citizen of the United States, have invented certain new and useful Improvements in Underframes, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a top plan view of an underframe constructed in accordance with this invention, substantially one-half of said underframe being broken away for the saving of space. Fig. 2 is a longitudinal vertical sectional view taken substantially on the plane of line 2—2 of Fig. 1. Fig. 3 is an enlarged transverse vertical sectional view taken on the plane of line 3—3 of Fig. 1, looking in the direction of the arrows, and illustrating the cross bearer construction. Fig. 4 is an enlarged 25 transverse sectional view taken on the plane of line 4—4 of Fig. 1, looking in the direction of the arrows, and illustrating the bolster construction. Fig. 5 is a further enlarged transverse fragmentary sectional 30 view taken on the plane of line 5—5 of Fig. 1, looking in the direction of the arrows, and illustrating the details of construction of the central portion of the bolster and showing the relative positions occupied by the center 35 sill and truss members at the bolster. Fig. 40 6 is a similarly enlarged longitudinal vertical sectional view taken substantially on the plane of line 6—6 of Fig. 1, looking in the direction of the arrows, and illustrating details 45 of construction at the bolster. Fig. 7 is a similarly enlarged horizontal fragmentary sectional view taken on the plane of line 7—7 of Fig. 6, and Fig. 8 is a horizontal 50 sectional view taken on the plane of line 8—8 of Fig. 3, illustrating details of the cross bearer construction.

The object of this invention is to provide a car underframe of substantial construction wherein the principal longitudinal mem-

bers are composed of commercially rolled 55 sections placed in such manner as to produce a maximum of strength with a minimum of parts.

A further object is to provide efficient 60 cross bearer and bolster structures particularly applicable to the design and arrangement of the longitudinal members.

The invention therefore resides particularly in the shape and relative arrangement 65 of the parts comprising the center sill and of the truss member of said center sill.

It further resides in the form of strut employed between the center sill and the truss member and the relation of said strut to the cross bearer.

It further resides in the novel design of 70 connection between the center sill and the draft sills and in their connection with the elements of the bolster.

Since the details of construction of the 75 underframe are identical upon opposite sides of the transverse median line thereof, only one side has been illustrated in the drawings and it will be understood that a description of one side applies equally to both.

Referring to the details, the numerals 1—1 indicate the side sills; 2 the end sills; 3 the body bolster; 4 the center sill; 5 one of the cross bearers of which there may be as many as may be desired throughout the 85 length of the car, and 6 the tie-bars intermediate the cross bearers and between cross bearers and bolster.

The center sill 4 comprises preferably an I section as 7 and a channel section as 8, the 90 I section being disposed with its web standing vertically and the channel having its web disposed horizontally and fixed to the upper surface of the top flange of the I section and having its flanges depending substantially 95 equidistant upon opposite sides of the I section.

The I section may obviously comprise a pair of channels placed back to back or it may even be replaced by a single channel 100 section if desired, within the scope of this invention.

Fixed to the bottom flange of the I section is a channel section 9 disposed with its web horizontal and with its opposite 105 flanges upstanding substantially equidistant upon opposite sides of the I section. The channel 9 is spaced away from the

- der surface of the I section intermediate the bolsters so that its end portions only are fixed to the I section, and its intermediate portion forms a truss for the center sill.
- 5 The spaced portion is connected to the under surface of the I section by a suitable strut 10, which comprises preferably a short length of longitudinally disposed I section disposed with its web in the same vertical plane with the web of the I section 7 and having upper and lower flanges fixed respectively to the lower flange of splice the I section 7 and to the top surface of the web of the channel 9, intermediate the flanges 10 of said channel. The I section 7 and the channel 9, and also the channel 8, are extended through the bolster, the I section and the channel 9 terminating short of the end of the channel 8 at a point between the end 20 sill 2 and the forward face of the bolster.

Within the bolster the down-turned flanges of the channel 8 and the upturned flanges of the channel 9 are connected by a pair of plates 11—11. The plates 11 are fixed to 25 the outer vertically aligned surfaces of said flanges and extend from a point behind the bolster, through the bolster, and approximately to the end of the channel 8.

The draft sills 12—12 extend from the 30 end sill 2 to a point within the bolster, each of said sills comprising a channel section disposed with its web standing vertical and its top and bottom flanges projecting outwardly. The inner surfaces of the webs of 35 the draft sills engage the outer surfaces of the splice plates 11 and are fixed thereto, preferably by rivets, some of which fix said plates to the flanges of the channel sections 8 and 9. Others of the rivets which fix the 40 plates 11 to the draft sills 12 serve also to connect the rear follower stops, as 13, of the draft rigging, to the inner surfaces of said plates. It will be observed in this connection that each of said follower stops 13 is 45 supported by rivets extending through a double thickness of metal, viz:—the plates 11 and the webs of the draft sills 12. As the splice plates extend through and beyond the bolster at each end and the top 50 and bottom channels 8 and 9 also extend through and beyond the bolsters it is evident that these members form a box like structure for part of the length of the sill. It is evident also that the top and bottom 55 channels 8 and 9 with their flanges also form a "box like" structure for part of the length of the sill though the vertical sides of the box are not connected as in the box comprising the splice plates 11.

60 The bolster comprises a pair of flanged diaphragms as 14—14 placed back to back at each side of the center sill and extending from the outer faces of the plates 11 to the respective side sills 1. The inner vertical flanges as 15—15 of the diaphragms are

riveted directly to the plates 11 and through said plates, to the flanges of the channels 8 and 9. The outer vertical flanges as 16—16 of said diaphragms are riveted directly to inner surface portions of the side sills.

Upper and lower bolster cover plates, 17 and 18 respectively, are fixed to the top and bottom flanges 19 and 20 of the diaphragms at opposite sides of the center sill, and extend across said center sill, the cover plate 17 being fixed to the top surface of the channel 8 and to the top flange of the I section 7, and the cover plate 18 being fixed to the bottom surface of the channel 9 and to the bottom flange of the I section 7. Each of the cover plates 17 and 18 terminate short of the outer ends of the bolster diaphragms. The cover plates 17 and 18 are also fixed to the inner ends of the top and bottom flanges of the draft sills and serve to materially strengthen the connection between the draft and center sills. Commercially rolled channel sections, such as those employed to form the draft sills 12, are not manufactured of a height so near that of the I section center sill as to compensate only for the thickness of the webs of the channels 8 and 9, and for this reason channel draft sills are employed which are of the same height as the I section and small fillers as 12^b—12^b are interposed between the top and bottom surfaces of the flanges of the draft sills and the contiguous surfaces of the cover plates 17 and 18, said fillers being of equal thickness with the webs of the channels 8 and 9, so as to present an even surface for the attachment of the cover plates.

A center bearing casting 21 and side bearing castings 21¹—21¹ are fixed to the under surface of the bottom cover plate 18, said center bearing casting being provided with the usual central king-pin aperture 22.

The bottom cover plate 18, the web of the channel 9, and the bottom flange of the I section 7, are each formed with perforations as 23—23 in alignment with the aperture 22. The web of the I section 7 is cut away as at 24 above the apertures 22 and 23 to admit the king-pin (not illustrated) and suitable semi-circular clips as 25—25 are fixed to opposite sides of the web of the I section, adjacent the cutaway portion 24, adapted to form an extension of the apertures 22 and 23 for retaining the king-pin in vertical position. Above the clips 25 the web of the I section is further cut away as at 26 to permit of convenient manipulation of the king-pin.

The cross bearer 5 comprises a pair of flanged diaphragms as 27 disposed upon opposite sides of the center sill. The inner vertical flanges 28 of the diaphragms are connected to opposite sides of the web of the I section of the center sill by through rivets. The outer vertical flanges 29 of the

diaphragms are fixed directly to vertical portions of the side sills. The top flanges 30 are connected together by a top cover plate as 31 which extends through a suitable aperture 32 formed in the web of the I section, said aperture being sufficiently removed from the top flange of the I section so that the cover plate extends beneath the lower edges of the downturned flanges of the horizontally disposed channel 8.

There is a strut 10 at the point of each of the cross bearers, and the inner vertical flanges of the diaphragms, comprised in said cross bearers, are continued below the bottom flange of the I section of the center sill and are fixed to opposite sides of the web of said strut by through rivets as at 32^a, a cut-away portion 33 being formed in each of the diaphragms to admit the flanges of the I section 7 and the upper flange of the strut.

The webs of the diaphragms 27 are disposed with one of their vertical faces approximately in the plane of a vertical transverse edge, or end, of the strut 10 and a connecting angle as 34 is fixed to the lower edge of the web of each of said diaphragms and extends across the edge, or end, of the strut for effectually binding the lower, or compression, portions of the diaphragms together.

The bottom flanges as 30^a—30^a of the diaphragms 27 are inclined from the side sills downwardly toward the truss channel 9 and engage the strut 10 at a point spaced somewhat above said truss. The side sills 1—1 are preferably of Z section though they may comprise any convenient or desired shape.

The Z sections illustrated are arranged with their webs standing vertically and their top flanges extending outwardly and adapted to support the side nailing strips as 35—35 upon their top surfaces. The top surfaces of said top flanges are arranged substantially in the same horizontal plane as the top surfaces of the upper flanges 30 of the cross bearers and are therefore below the level of the top surface of the center sill and the bolsters.

The top flanges of both the bolsters and cross bearers are horizontal from side sill to side sill so that the end flanges 16 of the bolster diaphragms project above the side sills and form pockets for the nailing strips 35. Upstanding angle sections as 36—36 are fixed to the webs of the side sills and to the webs of the diaphragms 27 at each of the cross bearers, for the same purpose.

What I claim is:

1. In a car underframe, the combination with a bolster, of draft sills extending thereto, and a center sill lapping the draft sills and comprising an I section and a channel section, said channel section being fixed to said I section and to the draft sills within the bolster.

2. In a car underframe, the combination with spaced draft sills, of a composite single center sill comprising a horizontally disposed flanged member fixed to each of said draft sills, and a vertically disposed member fixed to the under side of said horizontal member.

3. In a car underframe, a longitudinal sill comprising a vertically disposed member and a horizontally disposed member fixed to the upper edge of said vertical member, said horizontal member having marginal flanges depending substantially equidistant upon opposite sides of said vertical member.

4. In a car underframe, the combination with a bolster, of draft sills, and a composite center sill extending through said bolster and lapping said draft sills, said center sill comprising a vertically disposed member and a horizontally disposed member, one of said members having flanges extending upon opposite sides of said other member and each of said members extending along the longitudinal median line of the underframe.

5. In a car underframe, the combination with a bolster, and a single composite center sill comprising a rolled section with top and bottom flanges, and vertical web centrally disposed, said section extending through said bolster and lapping said draft sills, said center sill comprising also a plurality of superposed flanged members extending along the longitudinal median line of the underframe, and connected to said draft sills.

6. In a car underframe, the combination with a bolster, of draft sills, and a composite center sill extending through said bolster and lapping said draft sills, said center sill comprising a vertically disposed member and a horizontally disposed member, said horizontally disposed member having vertical flanges substantially equidistant upon opposite sides of said vertically disposed members.

7. In a car underframe, the combination with a bolster, of draft sills, and a composite center sill extending through said bolster and lapping said draft sills, said center sill comprising a vertically disposed member and a horizontally disposed member, said horizontally disposed member having vertical flanges lapping opposite sides of said vertically disposed member.

8. In a car underframe, the combination with a bolster, of draft sills, and a composite center sill extending through said bolster and lapping said draft sills, said center sill comprising a vertically disposed member and a horizontally disposed member, said horizontally disposed member having vertical flanges depending upon opposite sides of said vertically disposed member.

9. In a car underframe, a center sill comprising an I section, and a truss member for said center sill, said truss member comprising a horizontally disposed flanged member fixed to said I section at its ends and spaced therefrom intermediate its ends, the flanges of said truss member extending upwardly upon opposite sides of said I section.
10. In a car underframe, a single center sill comprising a vertically disposed I section, a truss member for said center sill, said truss member comprising a horizontally disposed flanged member fixed to said I section at its ends and spaced therefrom intermediate its ends, and an I section strut between said center sill and truss, the webs of said I section being in vertical alinement longitudinally of the underframe.
11. In a car underframe, the combination with bolsters, of a center sill comprising an I section, a horizontally disposed flanged truss member for said center sill spaced from said center sill intermediate said bolsters, and a strut between said center sill and truss member, said strut comprising an I section disposed with top flange fixed to said center sill and bottom flange fixed to said truss member.
12. In a car underframe, a single center sill comprising a vertically disposed flanged center sill member, a horizontally disposed truss member therefor, and a flanged strut between said center sill and truss, said strut having its web disposed substantially in vertical and longitudinal alinement with the web of said center sill member.
13. In a car underframe, an I section center sill member, a horizontally disposed channel section truss member therefor, and a strut between said center sill member and truss member, said strut comprising an I section with its web disposed substantially in the same vertical plane as the web of the center sill member.
14. In a car underframe, an I section center sill member, a horizontally disposed flanged truss member therefor, and a strut between said center sill member and truss member, said strut comprising an I section with its web disposed substantially in the same vertical plane as the web of the center sill member, and having its top flange fixed to said center sill and its bottom flange fixed to the web of said truss member.
15. In a car underframe, the combination with a bolster, of draft sills, and a composite center sill extending through said bolster, said center sill comprising a horizontally disposed member formed with vertical flanges fixed to said draft sills within said bolster, and a vertically disposed member formed with horizontal flange fixed to said horizontally disposed member.
16. In a car underframe, the combination with draft sills, of a composite center sill comprising a horizontally disposed member fixed to said draft sills, and a vertically disposed member fixed to said horizontally disposed member spaced intermediate said draft sills, and a truss member for said center sill being fixed thereto and to said draft sills.
17. In a car underframe, the combination with draft sills, of a composite center sill comprising a horizontally disposed channel section fixed to said draft sills, and an I section fixed to said channel section, and a truss member for said center sill fixed thereto and to said draft sills.
18. In a car underframe, the combination with draft sills, of a composite center sill comprising a horizontally disposed channel section fixed to said draft sills, and an I section fixed to the web of said channel section, the flanges of said channel lapping opposite sides of said I section, and a channel truss member for said center sill fixed to said draft sills.
19. In a car underframe, a longitudinal sill comprising a vertically disposed member and a horizontally disposed member, and a truss member for said sill, said truss member combining with one of said sill members to form a box-like structure enclosing the other of said sill members.
20. In a car underframe, the combination with a bolster, of a composite center sill comprising a horizontally disposed member and a vertically disposed member, splice plates and a truss member for said center sill, said truss member combining with said splice plates and one of said center sill members to form a box-like structure adapted for attachment of said bolster.
21. In a car underframe, the combination with draft sills and a bolster, of a composite center sill comprising a horizontally disposed member and a vertically disposed I-section centrally disposed, and a truss member for said center sill, said truss member combining with one of said center sill members to form a box-like structure adapted for attachment of said bolster and draft sills.
22. In a car underframe, the combination with a bolster, of draft sills extending thereinto, a composite center sill, extending relatively centrally between said draft sills, comprising a horizontally disposed member formed with flanges fixed to said draft sills, a vertical web and a truss member for said center sill, said truss member combining with said horizontally disposed center sill member to form a box-like structure adapted for attachment of said bolster.
23. In a car underframe, the combination with a bolster, of draft sills extending thereinto, a composite center sill comprising a horizontally disposed member formed with

- flanges fixed to said draft sills, and an I section fixed to said horizontally disposed member, a truss member for said center sill, said truss member combining with said horizontally disposed member to form a box-like structure inclosing said I section, and means connecting said horizontal member with said truss member adapted for attachment with said bolster.
24. In a car underframe, the combination with draft sills, of a composite center sill comprising a horizontally disposed member and a vertically disposed member, said vertically disposed member having a king-pin aperture formed therein.
25. In a car underframe, the combination with a bolster, of a center sill extending through said bolster, said center sill comprising a vertically disposed rolled flanged member formed with a king-pin receiving aperture.
26. In a car underframe, the combination with a bolster, of a center sill extending through said bolster, said center sill comprising a vertically disposed rolled flanged member formed with a king-pin receiving aperture through its flange and having its web cut away adjacent said aperture, and means fixed to said web adapted to form a vertical extension of the walls of said aperture.
27. In a car underframe, the combination with a bolster, of a center sill extending through said bolster, said center sill comprising a vertically disposed member and a horizontally disposed member, said first mentioned member being formed with a king-pin receiving aperture.
28. In a car underframe, the combination with draft sills, of a composite center sill comprising a horizontally disposed member fixed to said draft sills, and a vertically disposed member formed with a king-pin receiving aperture.
29. In a car underframe, the combination with a composite center sill comprising a vertically disposed member and a horizontally disposed member, of a truss member for said center sill, said truss member being formed with a king-pin receiving aperture, and the vertically disposed member of the center sill being formed with a king-pin receiving aperture in alinement with said first mentioned aperture.
30. In a car underframe, the combination with a composite center sill comprising a vertically disposed member and a horizontally disposed member, of a truss member for said center sill, said truss member being disposed centrally beneath said vertically disposed member, bolster diaphragms fixed to said truss member, and a bolster cover plate fixed to said truss member.
31. In a car underframe, the combination with a composite center sill comprising a vertically disposed member and a horizontally disposed member, of a truss member for said center sill, bolster diaphragms fixed to said truss member, and a bolster cover plate fixed to said truss member.
32. In a car underframe, the combination with a composite center sill comprising a vertically disposed member and a horizontally disposed member, of a truss member for said center sill, bolster diaphragms fixed to said truss member, a top cover plate fixed to said diaphragms and to said horizontally disposed member, and a bottom cover plate fixed to said diaphragms and to said truss member.
33. In a car underframe, the combination with a composite center sill comprising a vertically disposed member and a horizontally disposed member, of a truss member for said center sill, bolster diaphragms fixed to said truss member, a top cover plate fixed to said diaphragms and to said horizontally disposed member, a bottom cover plate fixed to said diaphragms and to said truss member, and aligned king-pin receiving apertures formed through said bottom cover plate, said truss member and the vertically disposed member of said center sill.
34. In a car underframe, the combination with a vertically disposed flanged center sill member, of a truss member therefor, a strut between said members, and a cross bearer extending in part through said center sill member and in part extending past and being fixed to said strut.
35. In a car underframe, the combination with a composite center sill comprising a horizontally disposed member and a vertically disposed member, of a truss member therefor, a strut between said center sill and truss, and a cross bearer member extending through the vertically disposed member, said cross bearer lapping said strut.
36. In a car underframe, the combination with a composite center sill comprising a horizontally disposed member and a vertically disposed flanged member, of a truss member therefor, a strut between said center sill and truss member, said strut comprising a flanged member disposed with its web in alinement with the web of the vertically disposed member of the center sill, a cross bearer extending in part through said vertically disposed member and in part extending past and being fixed to the web of said strut.
37. In a car underframe, the combination with a composite center sill comprising a horizontally disposed member and a vertically disposed flanged member, of a truss member.

member therefor, a strut between said center sill and truss, said strut comprising an I section disposed with its web in alinement with the web of the vertically disposed 5 member of the center sill, and a cross bearer extending in part through said vertically disposed member, said cross bearer comprising flanged diaphragms fixed to opposite sides of said strut and a compression

member extending past the web of said strut 10 and being fixed to said diaphragms.

In witness whereof I have hereunto set my hand in the presence of two witnesses.

VICTOR M. SUMMA.
